John Rawbortham
BY
W. C. Strawbridge

ATTORNEY.

UNITED STATES PATENT OFFICE.

JOHN ROWBOTHAM, OF PHILADELPHIA, PENNSYLVANIA, ASSIGNOR TO
JAMES BOYD, OF HAVERFORD, PENNSYLVANIA.

VALVE CONSTRUCTION FOR PUMPS.

No. 851,182.

Specification of Letters Patent.

Patented April 23, 1907.

Application filed January 12, 1906. Serial No. 295,758.

To all whom it may concern:

Be it known that I, JOHN ROWBOTHAM, a citizen of the United States, residing in the city of Philadelphia, county of Philadelphia, 5 State of Pennsylvania, have invented certain new and useful Improvements in Valve Construction for Pumps, of which the following is a specification.

This invention relates to a valve for pumps 10 of the construction in which the valve is adapted to be lifted from its seat by the action of the water or other fluid against its inner side, the said valve being returned, by suitable means, to its seat from which it was 15 lifted by the action of the fluid.

The object of my invention is to provide 20 means whereby when the valve is lifted from its seat it is given a slight rotation so that it will return to its seat in a slightly different position from that which it occupied before having been lifted therefrom, and at the 25 same time materially reducing the component of the force of the water striking against the valve, which is exerted transversely of the plane of the valve.

The purpose of rotating or shifting the 30 valve in this manner is to cause all portions of the under or seat surface of the same to come into contact with the seat so that one portion thereof will not be more greatly worn than another.

The purpose of materially reducing the 35 component of the force of the water or other fluid against the said valve as it escapes through the valve mechanism is to decrease the number of breakages of the supports for the valves.

A further object of my invention is to provide 40 means for facilitating the rotation of the valve and the means by which the valve is held upon or against its seat.

The objects and purposes for which the 45 invention is designed are effected by causing the travel of the water or other fluid through the openings or passageways provided in the valve seat in such directions that it will strike the valve at an acute angle, the result being that a certain component of the force of the escaping water occasions lifting of the valve, 50 while a certain other component of such force occasions the rotation or shifting of the valve. The relative proportions of these two components of the force of the escaping

water or fluid are dependent upon the angle at which the said water or fluid strikes the 55 valve as it escapes.

My invention resides in the combination and arrangement of the parts as hereinafter described, specifically pointed out in the claims, and as illustrated in the accompanying 60 drawings forming a part of this specification, and in which,

Figure 1 is a central vertical section of a 65 valve and its seat taken along the line 1—1 of Figure 2;

Figure 2 is a top plan view of the valve seat, a portion thereof being broken away;

Figure 3 is a sectional view showing the 70 curved or bent deflecting plates or ribs, the upper edge of each of which overlaps the lower edge of an adjacent plate or rib; and

Figure 4 is a similar view showing curved 75 or bent deflecting plates or ribs which do not overlap.

The valve seat consists of what may be 80 termed a hub 1, a ring 2, and deflecting plates or ribs 3 connecting the hub and ring, as is clearly indicated in Figure 2 of the drawings. The ribs 3 are inclined to the plane of the valve seat and are curved or 85 bent, as is clearly shown in Figures 1 and 3 of the drawings. It is to be understood that any construction in which one or more portions of the respective plates or ribs are angularly related to another portion or to 90 other portions thereof, whereby each of the said plates or ribs is concavo-convex in cross-section, is within the scope of my invention.

By inclining and curving the deflecting 95 ribs in the manner shown in Figures 1, 2 and 3, it will be observed that a construction is secured in which the upper edge portions of the said ribs are nearly parallel to the upper surface of the valve seat. In the construction as illustrated, there is a slight angle between the plane of the said seat and the upper portions of the said ribs, but the construction may be changed so as to make the upper edge portions of the deflecting plates 100 or ribs parallel with the plane of the valve or the angularity may be made greater than is shown without departing from my invention.

It will be observed upon examination of Figures 2 and 3, that the upper edge of 105 each plate or rib overlies or overlaps the

lower edge portion of an adjacent plate or rib. The object of overlapping the plates or ribs in this manner is to prevent the passage of any portion of the water or fluid through the valve in a straight or direct line against the valve 4 seated upon the valve seat.

In Figure 4 I have shown a modified construction similar to that shown in my application for patent pending in the Patent Office, filed January 12, 1904, Serial No. 188,744. This construction, although it decreases the vertical component of the force of the water or fluid passing through the valve mechanism, is found to be objectionable for the reason that a certain portion of the water or other fluid located between the dotted lines 5 passes in vertical or direct line through the said valve mechanism and thus renders the vertical component of the force greater than is necessary and also tends to prevent the rotation of the valve upon its seat. It will be understood that the upper edges of the ribs 6 shown in Figure 4 may be extended to different points and that with each extension a certain proportion of the objections noted is overcome, until finally when the upper edge of each rib reaches a point directly above or slightly beyond, as is the case in the construction shown in Figures 1 to 3, inclusive, all of the said objectionable features are overcome, the vertical component of the force being reduced to a minimum, and the rotation of the valve occasioned by the discharge of the water through the valve mechanism.

The hub 1 is provided with a screw-threaded perforation 10 which is adapted to receive a screw-threaded end of a projecting bolt 11, the upper end of which is provided with a screw-threaded portion which is adapted to receive a nut 12 for a purpose to be hereinafter stated.

The valve 4, which consists of rubber or other suitable material, is provided with a central perforation 13 through which the bolt 11 is adapted to pass. 15 designates a coiled wire spring which surrounds the projecting bolt 11. The lower end of the said spring is seated or rests upon a washer 16 provided with a seat 17 for the said spring. The washer 16 is provided with a perforation 18 through which the projecting bolt 11 passes. The upper end of the spring 15 presses against one side of a washer 20, loosely and rotatively mounted upon the projecting bolt 11. In order to facilitate the rotation of the valve 4, spring 15, and washer 20, I have provided a roller or ball bearing mechanism which is located between the washer 20 and the nut 12. 60 The bearing mechanism consists of a plate 21 having a central perforation or opening 22 therein, through which the projecting bolt 11 passes. The said plate 21 is provided with a plurality of openings 23 at points in-

termidiate its outer circumference and the 65 said central perforation 22.

24 designates rollers mounted in these openings, the diameters of which rollers are greater than the thickness of the plate 21. It will thus be seen that the washer 20 and the nut 12 are in contact with the rollers and not in contact with the plate 21, with the result that the force or pressure necessary to occasion rotation of the valve 4 and spring 15 is greatly decreased.

Only two of the openings 23 and rollers 24 are shown, but it will be understood that there should be at least one more opening and roller provided and as many more may be provided as are found to be practicable 80 and desirable. It will be understood, of course, that ball bearings may be substituted for the roller bearings shown.

In Figures 1 and 3, the arrows indicate the direction of travel of the water or other fluid 85 as it passes between the deflecting ribs 3 of the valve seat.

Having thus described my invention, I claim:

1. In a valve construction, the combination of a valve and a seat, the said seat comprising deflecting plates or ribs which are curvilinear in transverse section, whereby the inclination of the deflecting plates toward a horizontal plane may be increased at 95 and near the point of discharge from the said valve construction.

2. In a valve construction, the combination of a valve and a seat, the said seat comprising deflecting plates or ribs which are 100 concavo-convex in transverse section.

3. In a valve construction, the combination of a valve and a valve seat, the said seat comprising a hub, a ring, and deflecting ribs connecting the said hub and ring, the said 105 ribs being inclined to the plane of the said seat and being curvilinear in transverse section.

4. As an article of manufacture, a valve seat which comprises deflecting plates or ribs 110 which are concavo-convex in transverse section.

5. As an article of manufacture, a valve seat which comprises deflecting plates or ribs which are concavo-convex in transverse section, and the upper edge of each of the said 115 deflecting plates or ribs overlapping the lower edge of an adjacent deflecting plate or rib.

6. In a valve construction, the combination of a valve and a seat, the said seat comprising deflecting plates or ribs which are curvilinear in transverse section, and one of the edges of each of which plates or ribs overlies one of the edges of an adjacent plate or 125 rib.

7. In a valve construction, the combination of a rotatable valve and a valve seat, the

said seat comprising deflecting ribs which are concavo-convex in cross-section, means for pressing the said valve against the valve seat, and means for facilitating the rotation of the said valve.

5. In a valve construction, in combination, a rotatable valve, a valve seat provided with deflecting ribs or plates which are concavo-convex in cross-section, whereby the water or other fluid passing through the said valve seat between the said plates or ribs strikes the said valve at an acute angle, a projecting bolt secured to the said valve seat and upon which the said valve is rotatable supported,

a roller bearing mechanism secured at the 15 outer end of the said projecting bolt, and a coiled spring surrounding the said bolt and located intermediate the said valve and the said roller bearing mechanism and pressing against the roller bearing mechanism and 20 against the said valve.

In testimony that I claim the foregoing as my invention, I have hereunto signed my name, this 10th day of January A. D. 1906.

JOHN ROWBOTHAM.

In the presence of

LAURA KLEINFELDER,
HARRY F. AMBLER.
